UNITED STATES PATENT OFFICE.

JOSEPH A. V. TURCK, OF WILMETTE, ILLINOIS, ASSIGNOR TO FELT & TARRANT MFG. CO., OF CHICAGO, ILLINOIS, A CORPORATION OF ILLINOIS.

CALCULATING-MACHINE.

1,371,953.

Specification of Letters Patent. Patented Mar. 15, 1921.

Application filed July 8, 1918. Serial No. 243,826.

To all whom it may concern:

Be it known that I, JOSEPH A. V. TURCK, a citizen of the United States, residing in Wilmette, in the county of Cook and State 5 of Illinois, have invented a new and useful Improvement in Calculating-Machines, of which the following is a specification.

This invention relates in general to adding machines and has more particular reference to adding machines wherein the adding movements are induced from a suitable source of power and in response to the preliminary manipulation of appropriate keys so that the machine is key responsive, the 15 fingers merely manipulating the keys to govern each adding movement and in a multiple order machine to select the proper mechanism to receive the adding movement. The invention contemplates the provision 20 of a power-driven adding machine of compact construction and adapted for rapid, easy and certain manipulation.

An object of the present invention is the provision of a power driven adding machine, of the character above described, wherein the calculating actions will occur immediately upon or after the actuation of the keys by the operator so that the machine may be operated as rapidly as the operator can manipulate his fingers.

An object of the invention is to provide a power-driven adding machine in which the application of power from a continuously moving power member will be intermittently and positively applied to the accumulating mechanisms, and this as contradistinguished from the application of such power through frictional devices, although as the invention is better understood it will 35 be manifest that features of it may be used with advantage in power machines employing frictional connection between the prime driving parts and the driven members.

The invention has also for its object the provision of a power-driven apparatus having short and light key action to permit more rapid manipulation by the operator.

A further object of the invention is the provision of an adding machine having these and other advantages which will insure against improper key manipulation and this without the use of stops or other special devices provided for the purpose.

A still further object of the invention is

the provision of zeroizing devices of sure 55 operation with mechanisms of this character and so constructed and arranged that manipulation of the keys of the adding mechanisms during a zeroizing operation will neither interfere with the zeroizing 60 mechanism or make possible the jamming or injuring of any other parts.

A still further object of the invention is the provision of such zeroizing devices and mechanism of the character described which 65 by reason of its construction and operation protects the machine and all its parts from damage by violent and improper actuation of the zeroizing device.

Other objects and advantages of the invention will be apparent as it is better understood from the following description when considered in connection with the accompanying drawing illustrating a preferred embodiment thereof.

On the drawings,

Fig. 1 is a side elevation of a machine embodying my present invention;

Fig. 2 is a top plan view thereof;

Fig. 3 is a section taken substantially on 80 the line 3—3 of Fig. 4;

Fig. 4 is a partial detailed plan view with the casing removed, a portion of said view being taken above the top plate of the frame and a second portion being a section just 85 therebeneath;

Figs. 5, 6 and 7 are vertical longitudinal sections taken respectively substantially on the lines 5—5, 6—6 and 7—7 of Fig. 4;

Figs. 8, 9 and 10 are fragmentary sectional views showing the relative action of certain co-operative parts to be more fully described;

Figs. 11 and 12 are partial transverse vertical sections taken substantially on the 95 lines 11—11 and 12—12 of Figs. 5 and Fig. 4 respectively;

Fig. 13 is a partial enlarged fragmentary view showing the provision of bearings for the continuously moving power members; 100

Fig. 14 is a still further enlarged partial view of the same showing another section;

Fig. 15 is a partial vertical front to back section showing the zeroizing mechanism; and

Fig. 16 is a perspective showing the relations of the keys and certain parts directly co-operative therewith.

In the machine embodying my present invention now about to be described continuously moving power members are provided and these members are intermittently and 5 upon desired occasion positively connected with and actuate the parts driven by them. The manipulation of the keys by the operator serves merely to determine the extent and location in proper ordinal or denominational 10 places of the actuations causing the actuators and accumulating mechanisms to respond in movement in accordance with each particular key depressed by the operator, so that the machine may be said to be 15 key-responsive.

For the purpose of illustrating the invention, I have shown on the drawing a machine in which it is embodied. The working parts are mounted within a casing 25 of any usual 20 or preferred construction, through the top of which extend the key stems 26, each carrying a finger button 27, said button and stem constituting a digital pin, upon which suitable indications, as numerals ranging from 25 1 to 9 with their complements, are provided. The operative parts are carried in a frame located within this casing and consisting of skeleton plates 28 disposed between the denominational or ordinal sets of mechanisms 30 and at each side of the machine within the casing walls and tie rods or bars 29 are suitably arranged to connect said plates rigidly together and in certain instances to afford bearing pins or shafts for the moving parts. 35 A sub-top plate 31 (best shown in Fig. 4) is secured to the casing just beneath the top plate so that when the casing is taken off the keys will come with it and expose the internal mechanism. The keys are arranged in 40 orders and denominations, each order or denomination extending from the front to the rear, and, as stated, the key stems extend through the top of the casing. Each key stem 26 is rectangular in cross section and is 45 of relatively short length. A vertical slot 32 (Figs. 11, 12 and 16) extends from its lower end upwardly, providing two legs 33 and 34, one of which, 34 (the one at the left viewing the front of the machine), is somewhat 50 wider than the other, 33. The lower ends of each of these legs respectively extend through openings or slots 35 and 36 in the sub-top plate 31, so that each key stem is guided in its movement by the top of the 55 casing and the sub-top plate 31. Springs 37 are provided to hold the keys in elevated position, one end of each spring taking into a slot or recess 39 in the narrower leg. When a key is depressed the two legs 33 and 34 of 60 its stem are moved downwardly together through the openings 35 and 36 and arrange the mechanism for adding actuation, which occurs almost instantly.

The parts and devices of the several de-

nominations or orders of the machine are 65 exact duplicates of each other in the present instance and a description of one of them will suffice for the others. Viewing Fig. 7, it will be noted that two relatively long arms 41 and 42 extend up from adjacent the bottom of the frame to just beneath the plate 31. These arms are pivoted upon cross rods 40 and are connected at their tops at 43 with a differential bar 44, said arms being parallel and movable about their pivotal axes to 70 permit the bar 44 to have a longitudinal reciprocating movement. A spring 45 fixed at one end to a lug 46 on the forward arm 41, and at the other to a lug 47 on the under side of the bar 44, tends to move the arms 41 and 80 42 forwardly in the machine about their pivotal axes and to impart forward longitudinal motion to the bar 44. The top of the bar 44 is provided with a horizontally extending flange indicated at 48 in Fig. 4, which flange 85 is cut away at intervals at 49 to provide spaced openings adapted to be disposed beneath the key stem when the bar is in retracted position, and a plurality of stops or lugs 51 extend out beyond the flange 48. 90 When a key is depressed its leg 34 moves down through the appropriate opening 49, whereupon the bar 44 is permitted to move forwardly under the action of its spring 45, the portion of the flange 48 rearward of the opening 49, through which the leg of the key extends, passing through a slot 52 provided for the purpose. The bar 49 moves forward until a lug 51 engages the stem. The several lugs 51 are arranged rearwardly of the recesses at different distances, to provide a differential motion for the bar 44 in amount determined by the particular key of its order manipulated. It will be noted that the lug 51 back of the recess 49 at the left is nearer 105 the recess than the similar lug back of the recess 49 at the right. In the first instance the companion key is the "1" key and in the latter instance the "9" key.

It will be noted that the bar 44 is connected by a link 53 with one end or arm 54 of a skeleton lever 55 pivoted upon a cross rod or shaft 56. This lever is a segment lever that actuates the accumulator and has an arm 57 extending forwardly, which carries a toothed rack or segment 58, which actuates the accumulator. As the bar 44 moves forward, which occurs upon manipulation of a key of its order, the link 53 moves forward also and the rack 58 swings downwardly in an idle stroke, the amount of this movement being determined by a particular key depressed. That is to say, the movement is terminated when the appropriate lug 51 engages a key stem. A spring 59 fastened at one end to a lip 61 on the lever 55 and at the other end to a rod 62 extending across the machine aids the movement and reinforces

the action of the spring 45. The bar 44 is normally retained in position to hold the rack and arm or segment lever 55 elevated by a latch 63 pivoted upon a fixed rod 64 in the frame of the machine and engaging over a stud 66 carried by the bar 44. A spring 67 secured to a tail 68 of the hook or latch 63 and to a suitable part of the frame normally pulls the latch downwardly in clockwise direction (viewing Fig. 8) and into engagement with the lug 66. This latch is adapted to be released at each depression of a key by a mechanism to be now described.

A release bar 69 is provided beneath the legs 33 of the keys of each order and pivotally connected to yokes 71 and 72 pivotally mounted respectively upon cross rods 73 and 64 at the front and rear ends, each yoke having a perforation in its main part through which the rod passes and having wings 71' and 72' extending out at the side and returning upon themselves, the return portion being perforated also for reception of the rod. A lower bar 74 also connects the yokes 25 and this bar is connected by a spring 75 with a rear yoke 72, said spring and the bars and yokes being so arranged that the spring tends to swing the bar 69 upwardly. The release bar 69, yokes 71 and 72, and the lower 30 bar 74 are thus so arranged that the bar 69 may be lowered and retained in parallelism with its normal position and the yokes have a pin and slot connection 80 with the release bar for limiting the movement under key 35 pressure. The wing 72' of the yoke 72 is disposed immediately beneath and in contact with the latch or hook 63. The pivotal connections between the bar 69 and the yokes 71 and 72 are rearwardly of the axes of pivotal movement of the yokes and in almost horizontal alinement with them, so that when a key is depressed the bar 69 has nearly a true downward movement. This 40 swings the yoke 72 forwardly and lifts the wing 72' to release the latch. During this time the key is moving on down and when the latch is released the slot 52 in the leg 34 of the key is in registration with the flange 48 on the bar 44, which flange now moves 45 into the slot of the key, holding it down until the bar 44 is returned to normal position at the end of the adding movement, as will be later described. The differential bar 44 continues to move forward until the appropriate lug 51 engages the side of the key 50 stem and the machine is then set to have the number added into the accumulators by the action of the continuously moving power members now about to be described, it being understood that the segment lever has moved down an amount determined by the particular key of the order manipulated and the adding operative movement is the return 55 or upward movement of the segment lever.

A continuously rotating power shaft 91 65 extends transversely of the machine at the rear and has bearings at 92 in the frame of the machine, as indicated in Figs. 13 and 14. The bearing used in the present instance is a wood bearing saturated with some 70 lubricating material and indicated at 93. The wooden portion or bearing proper is provided on its outer surface with a dovetail shaped projection 94, which is embraced from one side by one part 95 of a 75 bearing housing and at the other by a second part 96, said bearing housing part having undercut flanges or ribs 97 engaging beneath the slanting portions of the dovetail projection. The two housing parts are 80 threadedly connected at 98 and one of them, 95, is provided with an upstanding flange 99 adapted to be disposed in contact with a part 101 of the frame. Two collars, 102 and 103, are also threaded onto the part 95 85 and against the opposite side of the frame member to lock the bearing in the frame. This form of bearing is used in the present instance because of the need of providing an easy running, substantially frictionless 90 bearing without the aid of a lubricant, which might ooze out upon the other parts of the machine or through the frame.

The shaft 91 is provided at its left-hand end with a crank 104 connected to a link 95 105, which in turn is connected to a crank 106 upon a shaft 107. By reason of this crank connection reciprocating or oscillating movement is continuously imparted to the shaft 107 and it is from this shaft that direct 100 production of the adding movement is accomplished. The shaft 107 passes clear across the machine and is provided adjacent each segment lever or arm 55 with oppositely extending arms 108 and 109 adapted to oscillate with the shaft. One of these arms extends upwardly and in the oscillating movement of the shaft is thrown forward and downwardly. This arm carries a dog 111 pivoted at 112 on the arm and having a 110 tail 113 above a stop pin 114 against which it is normally held by a spring 115. Under certain conditions when the arm 108 (Fig. 8) is moved in a clockwise direction it engages a tail 116 of a pawl 117 pivotally connected at 118 on the segment lever or arm 55 and spring-pressed in a clockwise direction, viewing Fig. 6, by a spring 119. The dog 117 engages in one of two teeth 121 and 122 in the upper end of a swinging bracket 120 arm 123, as best shown in Figs. 8-10, which arm is pivoted at 124 on the segment lever. A driving arm 125 is pivoted on the bracket arm 123, which, as will be later described, is positively and directly engaged to actuate 125 the segment lever when the segment lever has been lowered for an operative return stroke. The tail of the bracket arm is con-

nected by a spring 126 with the segment lever, such spring tending to move the arm in a counter-clockwise direction. A spring 120 is provided about the pivotal connection 5 of the driving and bracket arms and engages suitable lugs on the two arms to press the driving arm in a counter-clockwise direction (Fig. 5), movement in this direction being limited by the pivot pin 124 on the 10 bracket arm which engages the right-hand end of the driving arm. The dog normally engages the forward tooth 121, as shown in Fig. 8, holding the arm elevated.

Viewing Fig. 8, it will be noted that the 15 projection or arm 109 on the shaft 107 is provided with a driving pin 127 and in the oscillation of the shaft 107 this pin is swung in a counter-clockwise direction in its operative stroke. The arm 125 normally rests 20 above the arc of travel of the pin 127 and is adapted to be operatively arranged for engagement therewith by the shifting of the pawl 117 from the lower notch 121 to the upper notch 122 under the action of the stop 25 111. This action will be seen by comparing Figs. 8 and 9. The segment lever 55 when in upper raised position holds the pawl 117 out of the path of travel of the stop 111, so that in the mechanisms associated with the 30 banks of keys which have not been manipulated to lower the segment levers to operative position no action of the pawls 117 is produced by oscillation of the shaft 107. When, however, a key has been depressed 35 and the segment lever swung downwardly a corresponding or desired amount, the tail 116 of the pawl is moved into position to be engaged by the dog 111 to move the pawl out of engagement with the tooth 121 and into engagement with the notch 122. Of course 40 the pawl will assume different positions with respect to the path of movement of the dog, depending upon the amount of movement of the segment lever, and in order that in its 45 various positions the pawl may be properly engaged, it is somewhat elongated. In order that the driving arm may be accurately engaged when the segment lever has been lowered in response to the lower numeral 50 keys, the arm 125 is provided with a tail 131 adapted to move down upon the pin 127, and under certain circumstances acts as a 55 guide to insure engagement of the jaw 130 of the pawl with the pin 127. After oscillation of the arm 108 on the shaft to set the pawl 122 the shaft starts a movement in the reverse direction, swinging the arm 109 and its pin 127 in a counter-clockwise direction, viewing Figs. 8, 9 and 10, engaging the jaw 60 of arm 125 and moving the segment lever up to its normal position, which movement of the segment lever accomplishes the adding movement in the accumulator, as will be presently described. As the segment lever

returns to normal position the other parts, 65 *i. e.* the bars 44 and 69 and associated parts, are also returned to normal position and the latch 72 reengages the projection 66. After these parts are restored the pin 127 has a slight further movement which is enough to 70 swing the arm 125 and the bracket arm 123 about their pivotal centers and against the action of the springs 120 and 126, permitting the pawl to reengage in the notch 121.

The segment 58 of the segment lever is in 75 continual mesh with the pinion 141 upon a pinion shaft 142 extending across the machine and this pinion is connected by a ratchet 144 with a lantern wheel 143. The accumulator mechanism, which includes 80 these last mentioned parts and the numeral wheels 145 and connecting parts, is in the present instance substantially that of the well-known comptometer, fully described in Letters Patent of the United States No. 85 1,072,933 to Dorr E. Felt, issued September 9, 1913 and other patents to said Dorr E. Felt, and also in United States Letters Patent No. 1,110,734, and also mentioned in my co-pending application Serial No. 231,814, 90 filed May 1, 1918, for zeroizing mechanisms, and need not therefore be described in detail. It should be mentioned, however, that the lantern wheel 143 has fixed to it a pinion 140, which is the first of a chain of gears 145, 146 and 147 mounted respectively on shafts 148, 149 and 151, which connect the lantern wheel with the numeral wheel, the last mentioned gear, 147, being fixed to such numeral wheel. Suitable safety devices 100 against overthrow and back-latch and mechanism for carrying are provided, which need not be described here, except to state that the stops and safety devices engage the lantern wheel and that the carrying is actively 105 done in the first instance from one order to the next higher by a spring 152 attached to the gear 145 and to an escapement driving mechanism indicated generally at 153 in Fig. 7. As the numeral wheels are advanced power is stored up on these springs, which, after a numeral wheel has completed a summation of advances of ten steps, is released to impart a single step advance to the 110 next higher wheel. 115

Zeroizing is accomplished in the present instance in much the manner of my co-pending application mentioned, although it is believed that for certain purposes this zeroizing mechanism should be claimed in this 120 specification with other associated and co-operating parts. Zeroizing is accomplished in this machine quickly and without interfering with the normal operations of the machine by momentarily disconnecting the numeral wheel from the lantern wheel, which, as has been stated, feels the influence 125 of the stops and which by reason of the

stops prevents the power wound in the carrying spring from being lost after each adding actuation. Upon the breaking of this gear train the springs are free to turn the gears of the train behind the break in the connection to zero positions, stops being projected to halt the gear movements when the numeral wheels arrive at zero positions. To this end the shafts 148, 149 and 151 are mounted in swinging frames which have a pivotal movement about the bearing shaft 151. One of these frames is provided for each ordinal place and consists of a main downwardly extending plate 155 having an outwardly extending wing 156, which is returned inwardly, as indicated in Fig. 5, providing a secondary part 157 having bearing on the shaft 151 and having an offset part 158 slidably engaged with the forward end 15 of an appropriate skeleton main frame plate 28. The several ordinal frames are rigidly connected by cross rods 154 and in a measure by the shafts 148, 149 and 151, so that they may be considered to form a single frame having a pivotal axis about the shaft 151. Zeroizing is accomplished in the first instance by a short forward stroke of the lever 162 extending without the frame and visible more particularly in Figs. 1 and 2. This lever is attached to a shaft 163 extending within the casing and upon the shaft 163 is fixed an arm 164 (Fig. 15) normally spring-held against a stop 165 by a spring 166 connected at one end to a lug 167 on the 20 arm and at the other to a pin 168 on the right-hand side outer skeleton frame plate 28. This arm 164 carries at its end a roller 169 adapted to engage a cam face 171 on a swinging arm 172 pivoted at 173 on the 25 side skeleton plate 28. The arm 172 is connected by a link 174 with an arm 175 loose upon a shaft 176 and bearing against an arm 177 fixed on said shaft, the arms 175 and 177 being so arranged that they constitute in effect a single member. Extending rearwardly from the shaft 176 and arranged at intervals, one adjacent each ordinal or denominational set of mechanisms, is an arm 178 (Figs. 6 and 7), which arm is connected 30 with a curved link or lever 179 having a sliding fulcrum upon a cross shaft 181. This lever carries a pin 183 at its end which engages a lever 182 upon a cross rod 184 carried by the swinging frames. Each lever 182 forms one member of a toggle composed of it and a short arm 185 pivoted to one end of said lever 182 and pivoted also to a stud 186 fixed in the main frame of the machine. The pin 183 of the lever 179 engages with 35 in a bifurcated end 187 of the lever 182 and movement of this pin swings the toggle from one of its toggle-locked positions to the other. Viewing Fig. 7, it will be noted that springs 188 are secured at one end at 189 on the main frame of the machine and at the 40 other end to a rod 181 extending across the bottoms of the swinging frames, which springs tend to pull the swinging frame to hold the toggles in both of their locked positions, *i. e.*, with the toggles in position to maintain the gears in operative position and with the toggles arranged to disentrain said gears or break said connection between the numeral and lantern wheels. A relatively powerful spring 192 (Fig. 3) is connected to 45 arm 193 fast on the shaft 176 at the left-hand side of the machine and to a pin 194 in the main frame.

In zeroizing the lever 162 is swung toward the front of the machine, swinging in a clockwise direction the arm 164 (viewing Fig. 15). This causes the roller 169 to ride downwardly over the cam face 171 and until it engages in a stop recess 195. This movement swings the arm 172 upwardly and toward the left and through the link 174 imparts a forward movement to the arm 175. This movement of the arm 175 causes the toggles to swing from the position shown in Fig. 15 upwardly at their toggle connection, permitting the springs 188 to swing the frame downwardly and outwardly sufficiently to detrain the gears and release the carrying springs from the restraining influence of the stop devices on the lantern wheel and permitting the numeral wheels under the unwinding influence of said springs to return to zero position, where they are halted by the engagement of stops 201 upon the back of gear 145 with stops 202 which are swung upwardly into operative position by movement of the toggles and which need not be described in detail in this application since they are completely described in my co-pending application above-mentioned.

As soon as the lever 162 is released the spring 166 pulls back this lever on the arm 164 to normal position causing the roller 169 to move up and into engagement with a stop 203 at the upper end of the cam face 171 and by movement of the arm 172 in a reverse direction breaking the toggle locks which have been established upon the outward swinging of the frame. The spring 192, already mentioned, causes the shaft 176 to move over beyond the movement imparted to it by the action of the roller 169 on engagement with the stop 195 of the arm 172 and until the stop 204 engages the screw lug or projection 205 on the main frame, at which time the toggles controlling the action of the swinging frame are reestablished with the gears in operative mesh. This zeroizing mechanism already described in my co-pending application possesses particular advantage in coöperation with the segment lever control herein described and may be operated at any time without inter-

fering with the normal manipulation of the machine or requiring the operator to wait until any predetermined relation of parts is established for his zeroizing. It will be noted that this zeroizing mechanism merely starts the forward and return movements of the swinging frame relying upon yielding springs to complete such movements. A double acting ratchet 211 coöperating with 10 teeth 212 insures complete movement of the zeroizing lever in both directions.

It will be particularly noted that in this key-responsive machine the adding or accumulating mechanism is driven positively, and in instant response to the key settings, by the continuously running power device that becomes definitely connected with such mechanism for a definitely delimited and measured movement, without any dependence upon mere frictional or other action lacking positiveness. The continuously running power driving-mechanism must at the required instant definitely engage and grip the driven mechanism, without any possibility of slipping or lost motion, and must fixedly, and without any possibility of slipping or lost motion, retain the engaging grip upon such driven mechanism throughout the measured interval at whose end the driven mechanism must be abruptly disengaged and come to a sudden and definite stop, so that the movement of the adding mechanism shall be definitely delimited and never lag in beginning or slip back or be thrown ahead or be in any manner interrupted to the very end of its required amplitude. And this must be accomplished for constantly varying measures of adding movement, and separately in each of the many ordinal places of the machine, and always at a tremendous velocity imparted to mechanism that is necessarily extremely light and fragile, and notwithstanding the varying inertias involved in driving the driven mechanism for varying distances in each ordinal place and for varying numbers of the many ordinal places in the machine. The power must not only be continuously running but also great enough to pick up instantly any of the varying loads that may be placed upon it, and yet it must not impose any frictional or other wear or tear upon the light and fragile mechanism that it is intermittently and abruptly engaged with and disengaged from. The difficulty of providing such positively acting driving devices and connections is peculiarly great in such a key-responsive adding machine, in which the adding mechanism must respond instantly, and with extreme rapidity, to the lightest and swiftest play of the operator's fingers on the keys.

It is thought that the invention and many of its attendant advantages will be understood from the foregoing description, and it

will be apparent that various changes may be made in the form, construction and arrangement of the parts without departing from the spirit and scope of the invention or sacrificing all of its material advantages, the form hereinbefore described being merely a preferred embodiment thereof.

I claim:

1. In an adding machine, the combination of accumulators having numeral wheels, prime actuators, a continuously moving power member, and digitally responsive means for positively connecting the prime actuators to said power member to thereby permit said power member through the prime actuator to actuate the accumulators.

2. In an adding machine, the combination of accumulators including numeral wheels, a continuously moving power member, column actuators adapted to be set in appropriate positions by key actuation, means carried by said column actuators for receiving movement from said continuously moving power member and immediately operative automatic devices for arranging said means in position for subsequent positive actuation.

3. In an adding machine, the combination of key-controlled adding mechanism, and a continuous motion device with positive means acting between them, said means automatically, upon manipulation of the keys, establishing operative relation and subsequently positive connection between said adding mechanism and said continuous motion device.

4. In an adding machine, the combination of adding mechanism, a continuous motion actuating device, and means between said devices controlled by the adding device in its manipulative action and causing a positive connection between the said adding mechanism and the continuous motion actuating device to give registration of the digital manipulation in positive and negative calculation.

5. In an adding machine, the combination of adding mechanism, a continuous motion device, and means controlled by the manipulative function of the adding mechanism for producing a positive connection between the continuous motion device and the adding mechanism to give registration of the digital manipulation in positive and negative calculation.

6. In an adding machine, the combination of numeral wheels, actuating mechanism for said numeral wheels and shouldered digital controlling manipulative devices for said actuating mechanism; the said actuating mechanism being provided with means for moving it in a digital setting and having integral with it digital setting shoulders differentially spaced to those of the manipulative devices so as to give the nine varying

digital degrees of setting, and a continuous motion power mechanism that gives a positive return motion to the said actuating mechanism, thereby turning the numeral 5 wheel according to the digital setting.

7. In an adding machine, the combination of numeral wheels, actuating mechanism for said numeral wheels and digital controlling manipulative devices for said actuating 10 mechanism, said actuating mechanism being provided with a member common to all of the devices of an order for moving it differentially in a digital setting, the amount of said movement in each instance being determined by the manipulative devices so as to give the nine varying digital degrees of setting, and a continuous motion power mechanism immediately automatic for giving a positive return motion to said actuating 15 mechanism and thereby turning the appropriate numeral wheel according to the digital setting.

8. In an adding machine, the combination of adding mechanism, manipulative digital 20 control for said adding mechanism, a continuous motion actuating device for said adding mechanism and means between said adding mechanism and actuating mechanism immediately responsive to each digital manipulation for causing a positive connection 25 between the two said mechanisms whereby to transmit actuation to the adding mechanism to register each digital selection in immediate response to said manipulation.

30 9. In an adding machine, the combination of key controlled adding mechanism, a continuous motion actuating device and positive means acting between said adding mechanism and actuating device and immediately responsive to each key manipulation to give 35 an adding actuation.

10. In an adding machine, the combination of adding mechanism, column actuators, a continuously oscillatory power member, a 40 device rendered operable by movement of a column actuator for positively connecting said column actuator with said rotating member to produce the actuation of the column actuators through the column actuators 45 and accumulators.

50 11. In an adding machine, the combination of adding mechanism, digital manipulative controlling devices, a power member having a continuous oscillatory movement, column actuators arrangeable by said digital controlling manipulative devices for engagement by said member, movement of said member in one direction actuating the column actuators and through the column actuators 55 the accumulator mechanism.

60 12. In an adding machine, the combination of adding mechanism, digital manipulative controlling devices, a continuously rotating power member, a further member 65 driven thereby and having a continuous

oscillatory movement, column actuators arrangeable by said digital controlling manipulative devices for engagement by said member, movement of said member actuating the column actuators and through the column 70 actuators the accumulator mechanism.

13. In an adding machine, the combination of digital manipulative controlling devices, numeral wheels, actuating mechanism, a member differentially movable and in 75 amount determined by the particular manipulative controlling device for determining the adding movement to be imparted to the adding mechanism, said member engaging the particular manipulative controlling 80 device manipulated to determine its movement, a power mechanism for positively engaging said adding mechanism and operable immediately after movement of said differentially movable member to move said actuating 85 mechanism in accordance with an amount determined by said differentially movable member.

14. In an adding machine, the combination of adding mechanism, digital manipulative 90 controlling devices, a segment lever, a member differentially movable in accordance with the particular device manipulated and engaging said device to determine its movement for arranging said segment lever 95 in operative position, and power mechanism for positively engaging said segment lever to move it in accordance with an amount determined by said differential member.

15. In an adding machine, the combination of adding mechanism, digital manipulative 100 controlling devices, a segment lever, a member differentially movable in accordance with the particular device manipulated and engaging said device to determine its 105 movement for arranging said segment lever in operative position, and power mechanism for positively engaging said segment lever and operable immediately after movement of said segment lever to move it an amount 110 in accordance with the movement of said differentially movable member.

16. In an adding machine, the combination of adding mechanism, a power member having oscillatory movement, column actuators having a part engageable by said member and a tripping device for normally holding said part in inoperative position and operable under certain predetermined conditions to arrange said member for engagement 115 by said part to operate said column actuators and through said column actuators the accumulator mechanism.

17. In an adding machine, the combination of adding mechanism, a power member 120 having oscillatory movement, column actuators having parts engageable by said member on movement of said member in one direction for actuating said column actuators, and a tripping device for normally retain- 125 130

ing said parts free of engagement by said power member.

18. In a multiple-order key controlled calculating-machine, the combination with 5 a denominational series of the keys and a column actuator therefor, of a stop bar arranged at the side of the keys and mechanically connected to the actuator, and having separate stops one for each key, and each 10 adapted to contact with the stem of the key to which it corresponds, and thereby to arrest the actuator when it reaches the limit of the key's stroke, said stop-bar automatically locking other keys of the same denomination or series against actuation.

19. In a multiple-order key controlled calculating-machine, the combination with 20 a denominational series of the keys and a column actuator therefor, of a stop bar arranged at the side of the keys and mechanically connected to the actuator, and having separate stops one for each key, and each 25 adapted to contact with the stem of the key to which it corresponds, and thereby to arrest the actuator when it reaches the limit of the key's stroke, said stop bar automatically locking a key depressed against return movement until the calculation resulting from the depression of said key is completed.

30 20. In a multiple-order key controlled calculating-machine, the combination with a denominational series of the keys and a column actuator therefor, of a stop bar arranged at the side of the keys and mechanically 35 connected to the actuator, and having separate stops one for each key, and each adapted to contact with the stem of the key to which it corresponds, and thereby to arrest the actuator when it reaches the limit of 40 the key's stroke, said stop bar having flanges engaging all of the keys of its denominational series upon actuation of the key to lock said keys until the resulting calculation is completed.

45 21. In a multiple-order key controlled calculating-machine, the combination of continuously moving power mechanism, a denominational series of the keys and a column actuator positively moved thereby, of 50 a stop bar arranged at the side of the keys and mechanically connected to the actuator, and having separate stops one for each key, and each adapted to contact with the stem of the key to which it corresponds, and 55 thereby to arrest the actuator when it reaches the limit of the key's stroke.

22. In an adding machine, the combination of digital manipulative devices, adding mechanism, a member differentially movable in accordance with the manipulation of said devices for determining the subsequent actuation of said adding mechanism, said member being limited in its movement by engagement with said device and acting 60 65 as a lock to prevent subsequent manipula-

tion of other devices until after the adding movement of the adding mechanism under the influence of the actuator is completed.

23. In an adding machine, the combination of digital manipulative devices, adding mechanism, a member differentially movable in accordance with the manipulation of said devices for determining the subsequent actuation of said actuator mechanism, said member being limited in its movement by 70 engagement with said device and acting as a lock to prevent subsequent manipulation of other devices until after the adding movement of the adding mechanism under the influence of the actuator is completed, and a 75 continuously moving power member for engaging the actuating mechanism and moving it an amount determined by the movement of said differentially moving member.

24. In an adding machine, the combination of numeral keys, adding mechanism, actuating mechanism, and a member movable differentially in accordance with the particular key manipulated and limited in its movement by engagement with a key, 90 said member acting subsequently to lock other keys against manipulation until the completion of the adding movement.

25. In an adding machine, the combination of numeral keys, adding mechanism, 95 actuating mechanism, and a member movable differentially in accordance with the particular key manipulated and limited in its movement by engagement with the key, said member acting as a lock for the key 100 manipulated until after the completion of the adding movement.

26. In an adding machine, the combination of a column of nine keys, adding mechanism, actuating mechanism, and a member 105 movable differentially in accordance with the particular key manipulated, said member being limited in its movement by engagement with said key and serving to lock all of said keys until completion of the adding movement in the adding mechanism.

27. The combination of digital controlling manipulative devices, numeral wheels and actuating mechanism for said numeral wheels immediately responsive to said digital manipulative controlling devices, said actuating mechanism including a segment lever and a driven rock shaft having connections for actuating said segment lever to produce advance of said numeral wheels.

28. The combination of digital controlling manipulative devices, numeral wheels and actuating mechanism for said numeral wheels immediately responsive to said digital manipulative controlling devices, a continuously rotating shaft and a rock shaft operated thereby to produce advance of said numeral wheels by said actuating mechanism.

29. The combination of digital controlling

- manipulative devices, numeral wheels and actuating mechanism for said numeral wheels immediately responsive to said digital manipulative controlling devices, said actuating mechanism including a rack member and a rocking drive shaft for selectively engaging and actuating said rack member to produce advance of said numeral wheels by said actuating mechanism.
- 5 30. In an adding machine, the combination of power mechanism, adding mechanism and, coöperating therewith, key responsive rack members having a part normally out of engagement with the power mechanism and adapted after actuation by the key to be moved by the power mechanism into position for engagement by said power mechanism, said power mechanism thereafter actuating said rack members to drive 15 said adding mechanism.
- 10 31. In an adding machine, the combination of power mechanism, adding mechanism and, coöperating therewith, key responsive rack members having a part normally out 20 of engagement with the power mechanism and adapted after actuation by the key to be moved by the power mechanism into position for engagement by said power mechanism, said power mechanism thereafter 25 positively actuating and engaging said rack members to drive said adding mechanism.
- 25 32. In an adding machine, the combination of accumulator mechanism, an actuator therefor and movable into various positions 30 for adding, a continuously moving power member and a member carried by said actuating device and movable in timed relation to said power member into its path to permit engagement thereby and actuation of 35 said actuator from said power member.
- 30 33. In an adding machine, the combination of accumulator mechanism, manipulating devices, a power member, an actuator movable upon manipulation of said devices 40 into various adding positions and movable into various operative positions for adding and having a member movable in timed relation with respect to said power member and 45 into the path of said power member whereby to permit said power member to actuate said actuator.
- 5 34. In an adding machine, the combination of accumulator devices, manipulative devices, a power member, segment levers immediately responsive to said manipulative devices and having members movable in timed relation to said power member and into its path, for permitting said power members to engage and move said segment levers.
- 10 35. In an adding machine, the combination of adding mechanism, a plurality of prime actuators adapted to be independently set into operative positions, and a continuous motion device for positively actuating said prime actuators, one said prime actuator being capable of being set during the actuation of another said prime actuator by said continuous motion device.
- 15 36. In an adding machine, the combination of adding mechanism, a plurality of prime actuators adapted to be independently set into operative positions, and a continuous motion device for positively actuating said prime actuators, one said prime actuator being capable of being set before the completion of the actuation of another previously set prime actuator.
- 20 37. In an adding machine, the combination of adding mechanism, a plurality of prime actuators adapted to be independently set into operative positions and a continuous motion device for positively actuating said prime actuators, the action of the continuous motion device being individualized to said prime actuators and leaving other prime actuators in manipulative condition.
- 25 38. In an adding machine, the combination of adding mechanism, a plurality of prime actuators adapted to be independently set into operative positions and a continuous motion device for positively actuating said prime actuators, said continuous motion device having all its operative and inoperative travel along a fixed and permanent path of movement.

JOSEPH A. V. TURCK.
